UNITED STATES PATENT OFFICE.

JOHN ROBINSON KELSEY, OF BRISTOL, ENGLAND.

HAT-SHAPING MACHINE.

SPECIFICATION forming part of Letters Patent No. 295,650, dated March 25, 1884.

Application filed November 20, 1882. (No model.)

To all whom it may concern:

Be it known that I, JOHN ROBINSON KELSEY, a subject of the Queen of Great Britain, and residing at Bristol, England, have invented 5 a new and useful Improvement in Hat-Shaping Machines, of which the following is a specification.

The invention relates to certain improvements on the hat-shaping machine patented to me June 27, 1882, No. 260,298; and it consists, first, in the arrangements whereby the upper ends of the rods which support the pressers or formers may be adjusted nearer together or farther apart; second, in the novel construction of the side curlers; third, in the devices for rendering the upward pressure of the dish or mold adjustable; and, fourth, in the novel arrangement of the rods and levers for moving the curling devices.

20 In the accompanying drawings, Figure 1 is a front elevation of the machine. Fig. 2 is a cross-section of the dish or mold and its attachments. Fig. 3 is an exterior perspective view of the mold and its attachments and of 25 the pressers or formers above. Fig. 4 is a section through the table and side curlers. Fig. 5 is a partial section, showing the method of connecting the presser-rods with the cross-head. Fig. 6 is an elevation of the front or 30 back clamp.

Similar letters of reference indicate like parts.

A is the frame of the machine. A' is the table; B B, uprights thereon; C, the cross-head, guided on posts D D when moved down by the treadle E through the rods F, or up by the counterpoise G, the treadle being hung from a pivot-bar at the back of the frame. In the cross-head C are formed slots I.

40 J J are rods, the upper ends of which are forked, as shown in Fig. 5. Said forked ends receive between them the cross-head C, and a nut or threaded sleeve, K, is inserted through an aperture in one of the forked ends of each 45 rod and through the slot in the cross-head. Through each of the other forked ends of the rods J is inserted a screw-bolt, L, which enters the nut or sleeve K. It will be seen that by loosening the bolt L the upper end of the 50 rod J may be moved as desired lengthwise of the slot I. The rods J pass through the guide or top-stay H, and are pivoted to knuckle-le-

vers M, and to their lower ends are attached by bolts the pressers or side-formers N. O, Figs. 3 and 4, is the dish or mold on which the 55 hat to be operated upon is placed, and P is a block which enters the body of the hat and sustains the same. When the treadle is pressed down, the cross-head C descends and the rods J are caused, through their connection with the 60 knuckle-levers M, to describe a peculiar curvilinear motion, to enable the formers N to be placed against a hat-body resting upon the block P and mold O. The degree of separation of the formers, as they finally press upon 65 the hat, is obviously dependent upon the separation between the upper ends of the rods J. By bringing these ends nearer together or separating them more widely, I am thus enabled to govern the distance between the formers, and so to adjust the latter to suit larger or 70 smaller hats.

The mold O is provided with a cylindrical recess to receive a projection, R, formed upon the table. On the upper side of the mold is 75 placed the block P, which receives the small projection S, and is prevented from sidewise motion thereby.

In the table I arrange a sleeve or nut, T, to receive the screw U. Said screw is provided 80 with reverse threads, as shown in Fig. 2, and its upper portion enters the mold O. Surrounding the screw and placed between mold and table is a spiral spring, V. By suitably turning the screw U the mold O will be caused 85 to move up or down, and the spring V will thus be more or less compressed, and so will offer a greater or less resistance to the descent of the mold when the latter is pressed upon by the formers. By this arrangement 90 I am enabled to graduate the resistance or upward pressure of the mold O in accordance with the nature of the material being operated upon.

W W are brackets or supports provided 95 with flanges which enter guides on the table. Beneath said brackets the table is slotted, and through said slots pass pins, X, connecting the brackets to the levers, by which they are caused to move longitudinally on the table. 100 To said brackets are adjustably attached, by means of the screws Y, the curling-boxes Z. Said boxes are metal castings having rounded edges, a, and being generally shaped as shown

in Fig. 4. The boxes thus constructed take the place of the side boxes and separate curling-flanges attached thereto shown in my previous patent before referred to, the present 5 construction being simpler, stronger, and more easily made. The edges *a* of the boxes *Z* form the curling-flanges. The boxes *Z* are arranged so as to have a slight up-and-down play, and through them pass screw-bolts *b*. Between 10 said screw-bolts and the boxes are placed springs, *c*, which press down upon the boxes and hold them in place. When the edges *a* of the boxes act upon a hat-brim, as hereinafter described, the springs *c* yield slightly and 15 allow the edges *a* to rise sufficiently to prevent their cutting of the material. On the boxes *Z* are pins *d*, which enter diagonal slots in the front and back clamps *e*. The pins *X* connect the brackets *W* with levers *f*. Said levers are pivoted to the ends of a bar, *g*, which is pivoted to the table and provided with a handle, *h*. By moving said handle in one or the other direction, the levers *f* cause the brackets to approach or recede from each 25 other.

The operation of the machine is as follows: By means of the screw *U* the mold is adjusted so that the degree of its yielding to the pressure of the formers shall be suitable to the hat 30 material to be treated. By means of the screw-bolts *b* the curling-boxes *Z* are similarly adjusted. By means of the bolts *L* the upper ends of the rods *J* are adjusted on the cross-head *C* so that the formers *N* shall approach each other 35 to a suitable degree to fit the size of the hat being treated. These adjustments being made, the brim of the hat is rendered soft and pliable by the aid of a "baker" or brim-warmer, which is independent of the present machine. 40 The hat is then placed over the block and upon the dish or mold *O*. The lever *h* is suitably moved to separate as widely as possible the curling-boxes. By pressure of foot upon the treadle *E* the formers *N* are caused to descend 45 upon the brim, and they are forced down until the dish or mold *O* is carried downward as far as the spring *V* beneath it will allow. The lever *h* is then turned so as to cause the curl-

ing-boxes *Z* to approach each other. As this movement of the boxes *Z* continues, their edges 50 *a* meet the edge of the hat-brim and turn said edge over the formers, which remain tightly pressed down. As the boxes *Z* approach each other the front and back clamps, through the movement of the pins *d* in their diagonal slots, 55 are caused to slide upon said boxes *Z*, and simultaneously with the edges *a* of the latter, to act upon the hat-brim. After the hat is thus shaped, the lever *h* is thrown back and the foot is removed from the treadle. The formers are 60 then detached from the rods and removed from the hat, as fully set forth in my previous patent before referred to.

I claim—

1. In a machine for shaping and setting hat-brims, the two suspended presses, in combination with means for adjusting the distance between the ends to which the divided curling-ring is attached when depressed and acting upon the hat, substantially as described. 65

2. In a machine for shaping and setting hat-brims, the combination of the forked rod *J* and slotted cross-head *C*, bolt *I*, and sleeve or nut *K*, substantially as described. 70

3. In a machine for shaping and setting hat-brims, the combination of the dish or mold *O*, reverse-threaded screw *U*, nut *T*, spring *V*, and table *A'*, substantially as described. 75

4. In a machine for shaping and setting hats, the curling-boxes *Z*, adjustably attachable to the brackets *W*, and arranged so as to have an up-and-down motion, substantially as and for the purpose described. 80

5. In a machine for shaping and setting hats, the combination of the curling-boxes *Z* with the screw-bolts *b* and springs *c*, substantially as described. 85

6. In a machine for shaping and setting hat-brims, the combination, with curling-boxes, of the brackets *W*, pins *X*, levers *f*, and lever *g*, all arranged and operated substantially as described. 90

JOHN ROBINSON KELSEY.
